FLOATING ROOF WITH FLEXIBLE DECK
AND CENTRAL WEIGHTSReign C. Ulm, East Chicago, Ind., assignor to
Graver Tank & Mfg. Co., Inc., East Chicago,
Ind., a corporation of Delaware

Application September 7, 1950, Serial No. 183,612

5 Claims. (Cl. 220—26)

1

This invention relates to floating roofs as used mainly for vapor conservation in the storage of gasoline and other volatile liquids. It provides greater efficiency and economy in floating roofs, particularly of the single-deck type.

Basically, a floating roof according to this invention is an improvement over the floating roof disclosed and claimed in Patent No. 2,497,047 of Frank D. Prager and myself, hereinafter called the Prager-Ulm roof. The corrosion-resisting self-draining nature of the Prager-Ulm roof, with a smooth inward-downward slope, is maintained more safely and more completely by means of the present invention.

The main part of such a roof, a substantially unreenforced, flexible, centrally weighted and centrally drained deck the underside of which contacts the liquid, is modified as to its operative and inoperative shapes, in accordance with this invention, whereby it is materially improved as to the safety, completeness and accuracy with which the roof maintains its corrosion-resisting, self-draining nature in its various operating—that is, floating—conditions.

The shape of such a deck, in vertical cross-section, is not the same, under different conditions, although the changes are seemingly small. As pointed out in Patent No. 2,497,047, such a deck is extremely flexible; if not held or tensioned in some manner it behaves almost like a large, thin leaf floating on water. Thus it can be called a metallic membrane deck. The contour of the membrane deck, as originally constructed, hereinafter called the "construction curve," is influenced by the fact that the deck is shored up or supported, against its own weight, at distributed points or lines. The corresponding contour of the membrane deck, when in floating condition, is different, being subject to different factors and forces. This latter contour, hereinafter called the "operating curve," is influenced by the fact that the deck tends to bulge or curve upwards due to the pressure of the displaced liquid; the deck being weighted down locally, by the central ballast weight and the peripheral rim and seal. Strictly speaking, different operating curves exist under different operating conditions. For instance, a snow load on the roof affects this curve. Still another contour exists when the deck is not shored up and not supported by liquid; I call it the "dry suspension curve."

The change of contour of the deck, between these different curves, is allowed by the flexible, substantially unreenforced deck construction.

2

However, I have discovered that it is desirable, and possible, to minimize this change, or the actual amount of flexing.

For this purpose I prefer to eliminate several factors present in the original Prager-Ulm design, which added to the actual amount of flexing in some important parts of the deck.

One such factor, eliminated in the roof as shown here, was the use of different and more rigid plate material in the center of the roof. I prefer to construct a circular, flexible membrane deck comprising substantially the entire area of the floating roof, substantially unreenforced and unobstructed except at the required, 10 peripheral, rigid, upstanding rim; and I usually employ lap-welded metal plate material of uniform thickness throughout this circular area. As a result the inward pull of the central ballast weight is imposed on the flexible membrane 15 deck somewhat more directly.

This applies even in the event that the central, weight-supporting part of the deck is reinforced to some extent by drainage channels or the like, which may be welded to the top of 20 the deck in this central part. However, I prefer to eliminate or modify such channels also; not so much for structural as for functional 25 reasons connected with the prevention of trouble due to ice and the like. Still further flexibility 30 of the central deck section results from this further change, although I may keep the central ballast weight rigid by reinforcements in its upper part.

The relatively flexible central part of my new 35 and improved floating roof tends to curve downward, as a result of the weight of the ballast material which is substantially distributed over the same. I may or may not counteract such downward curvature, depending on details of the 40 central reinforcements which I will explain. Depending on such modifications the contour of the new roof may have different types of curvature, as will be explained hereinafter.

A final factor of the original Prager-Ulm idea 45 which added to the actual amount of flexing, had to do with the method of constructing the deck. The construction curve was a flat, straight-sided cone. As pointed out in my co-pending application S. N. 122,639 filed October 21, 1949, I prefer to provide this construction 50 curve with an upward curvature over a part of the radius between the inner and outer parts thereof, thereby making it very similar to the normal operative or floating shape of the deck.

The aforementioned modifications add to the

flexibility of certain central parts of the roof, while the actual amount of flexing between different conditions of the roof is reduced, as mentioned. As a result I practically avoid the danger of certain local irregularities in the operating curves of the deck. I found that such a danger exists in the original form of the Prager-Ulm roof, except when keeping the flexing strains and stresses within rather narrow limits. When such limits are exceeded, in said original form, local irregularities tend to develop, mainly if the deck construction is relatively simple and rugged. Such local irregularities consist largely in radial bulges and furrows, whereby the deck surface becomes wavy, and the removal of corrosion-inducing rainwater and vapor is hindered. Such radial bulges and furrows induced by excessive flexing strains are different in shape and usually less serious in nature than are the bulges and depressions characterizing still earlier decks, involving the use of heavy reinforcements over the deck-area. It is obviously desirable to practically eliminate all bulges and irregularities which tend to retain corrosive materials. This is achieved by the present invention. It may be noted that it is achieved with a centrally more flexible roof, which is cheaper to build than the original form of the Prager-Ulm roof.

I will now describe a preferred form of the new roof. In view of the great importance of relatively small flexural changes it will be necessary to specify certain dimensions and proportions. No attempt will be made, of course, to present actual shop details, and it will be understood that certain dimensions are shown for purposes of illustration rather than limitation.

Figure 1 is a cross-sectional elevation and Figure 2 a plan view of the preferred embodiment of the present invention. The floating roof tank represented in these figures will be assumed to be about 40 feet high and about 120 feet in diameter.

Figure 3 is a partial cross-sectional elevation of the floating roof, on a scale larger than that of Figure 1 as to the horizontal dimensions and much larger as to the vertical dimensions; this distortion being necessary in order to disclose important features of the construction and operating curves. The approximate ratio of horizontal to vertical dimensions in this figure is somewhere in the vicinity of 1:50. The thickness of the deck plates is somewhat exaggerated, in order to avoid confusion between different lines.

Figure 4 is a modified detail from Figure 2, with further enlargement of the horizontal dimensions; no vertical dimensions being shown in this view.

Figures 5 and 6 are sections through Figure 4 along lines 5-5 and 6-6 respectively. Both horizontal and vertical dimensions are still more enlarged in these two views, as compared with Figures 1, 2 and 4; they are enlarged in approximately the same ratio.

Figure 7 is a diagram, representing the embodiment of Figures 5 and 6 in a single figure and emphasizing the vertical dimensions.

The storage tank 10, with cylindrical shell 11 and circular bottom 12, contains the volatile liquid or product 13, often a sour crude, which is admitted and withdrawn through suitable openings and conduits (not shown). The top of the tank is open, eliminating the cost of a fixed roof with structural supports.

The floating roof 14, substantially unreinforced and flexible in accordance with the Prager-Ulm disclosure and thereby additionally contributing to the overall economy of the apparatus, floats on the surface of the product 13. It covers all but a minor, annular, peripheral area of this surface and protects the bulk of the volatile liquid from contact with the atmosphere and from the influence of the wind, thereby greatly reducing the tendency towards evaporation and vapor loss. A single-deck floating roof of the so-called pan type is used.

In accordance with the Prager-Ulm disclosure this roof comprises a flexible membrane deck 15, the entire underside of which is in contact with the product 13; a rigid upstanding rim 16 around the periphery of the deck; and a large and heavy body 17 of ballast weight material 18 permanently installed upon, limited to and substantially distributed over an inner, concentric portion of the deck surface. The body 17 is heavier than the underlying, inner deck portion 19. It is higher than the slightly sloping deck, but it is also much wider than high. It is installed above the underlying and surrounding deck surface.

A suitable drain 20 is connected to the center of the deck 15, to allow removal of rainwater from the roof surface. A seal 21 practically closes the annular space around the deck. When the tank is drained, for instance for the removal of sediment from the bottom, the deck is supported by legs 22 equally spaced along the rim portion 16, and sometimes by similar legs spaced around and adjacent the ballast weight 17.

Reference is made to Figure 16 of the Prager-Ulm drawing and, particularly to, the curve 63 which represents the contour of the deck along one radius in normal operating position. As pointed out in the pertinent specification the curve 63 is almost horizontal, but has, at least some upward-outward direction everywhere; the inclination being sharper near the center of the deck than in the outer parts thereof.

The approximate shape of the deck, with such inclination is shown in Figure 1. It is analyzed in some detail in Figure 3. It will be noted that in the embodiment as shown the entire deck has an inward-downward slope, with a double sigmoid curvature along each radius. This curvature is shown as convex to the bottom in outer and inner areas of the deck, due to local rim and ballast weights supported by the deck in such areas. It is convex to the top in a large, intermediate, annular area of the deck, due to the buoyance of the displaced liquid product. Details of this curvature are subject to change mainly in the central part of the deck, but an upward curvature substantially as described is always present in the floating condition of this deck.

The total slope of the deck, from the rim to the ballast weight may be about a foot, in a deck of 120 feet diameter, and the rise of said upward curvature may be several inches. The rim section, reinforced by $\frac{1}{4}$ " or similar steel plate, is about 5 to 10 feet wide and about 2 to 3 feet high. The ballast weight, formed mainly of gravel and the like, has a diameter of about 30 feet and a height of 2 to 3 feet. The deck is usually formed of $\frac{1}{8}$ " steel plates, lapwelded as indicated in Figure 3.

The operating shape of a deck in accordance herewith is substantially predetermined. This shape is approximated, as mentioned, by the

"construction curve" in accordance herewith, in order to minimize the actual values of deflection Z as defined in Patent 2,497,047. By this expedient I also minimize the actual values of the radial elongation or strain in the plate material. This again minimizes the peripheral strain, and the peripheral stresses connected therewith. In this manner I minimize peripheral compression forces in the body of the deck, which would otherwise tend to produce radial bulges or wrinkles.

The theoretical shape of the construction curve, for deck 15, is shown by line A in Figure 3 hereof. It is theoretical insofar as it disregards the sudden steps due to the lapwelds between the plates. These are shown by line B. Of course, as mentioned initially, the figure exaggerates the thickness of the plates and therefore the magnitude of the sudden steps, nevertheless these steps have actually appreciable magnitude in proportion to the total rise of the line or curve. When reference is made to the construction curve, hereafter, the actual curve B is meant except if the context is different.

Lines A and B rise outwardly at least to some slight extent throughout the extent of the lines and the rise is such that the outer, annular part 23—forming an integral part of the deck about $\frac{1}{8}$ " thick—is curved downwardly or concave to the top. In some instances, if the rim 16 and the seal 21 are relatively light, the outer annular part 23 may not be actually concave to the top, but it is never bulged upwards to the same degree as is the intermediate ring 24.

The innermost circular part 19 of the floating roof is another integral part of the deck, in accordance herewith.

The original form of the Prager-Ulm roof was based on the use of special, strong plate means 36, 37, 38, 39 and 41 for these innermost and outermost parts of the deck. I have discovered that this is unnecessary, and I prefer to use steel plates of identical thickness—usually $\frac{1}{8}$ "—for the entire deck.

As in the earlier construction, the rim portion 26 of the deck 15 is reenforced by structural means, including gussets 27. The center portion 19, below the ballast material 18, may be reenforced by drain channels 28.

In the construction of the roof, the construction curve B is suitably impressed on the deck, for instance in the manner disclosed in my said copending application. This involves the use of suitable shoring-up supports (not shown). When these supports are removed, upon completion of the construction process, the deck tends to assume a contour defined by the "dry suspension curve" E in Figure 3. Substantially the same curve is shown at a different scale, in Figure 10 of the Prager-Ulm disclosure.

The tank is then filled and the normal operating curve C is gradually established thereby. It must be understood that in accordance with my new invention, this establishment of the normal operating curve C constitutes very nearly the reestablishment of the construction curve A.

Due to the fact that the present deck tends to return from the dry suspension curve E to the construction curve B, and that the latter resembles the normal operating curve C, a minimum of distortion is involved in the full and extreme change between operative and inoperative (dry) conditions. This minimum of distortion again, involves a relative minimum of stress differentials between said extreme conditions. Inasmuch as all stresses—whether radial or an-

nular—increase and decrease together, although not at the same rate, I provide a relative minimum of annular tension and compression, and a relative minimum of bending moment, between the extreme conditions.

Otherwise, very considerable bending moments could be developed, tending to seriously warp the deck and even the rim. I have determined this point by testing different floating roofs with central weights, and accurately measuring the stresses as well as deflections, along different radii.

The relative smallness of stresses and strains in my improved floating roof allows the use of relatively thinner, peripheral and central deck plates, as indicated above; also the use of a relatively weaker, lighter and cheaper rim and reinforcing system for the same. Moreover the new and improved deck surface is particularly smooth and free from local irregularities, such as the radial bulges, wrinkles or wavy surfaces mentioned above.

This absence of irregularities in the deck simplifies the maintenance of the floating roof. Corrosive accumulations are practically non-existent, above and below the deck. After a rain fall, and after the melting of snow, all of the water drains away; no residual pools are formed, which would be removed only by slow evaporation.

Equally no layers of vapor in gas phase are formed anywhere below the deck; at most, bubbles of vapor are formed, moving through the product in liquid phase. This, again, contributes to the vapor economy. Where extensive layers of vapor are formed under a metal deck, as in prior floating roofs where vapor accumulating spaces were intentionally or inherently formed, such layers act as thermal insulators, postponing both the heating up and the cooling down of the product during the daily temperature cycle. However, such layers of vapor also promote evaporation; in fact the existence of an interface, between a body in liquid phase and one in vapor phase, is one of the main requirements for evaporation. Inasmuch as my improvement reduces the chance for the formation of such layers or bodies in vapor phase, it also resists the formation of such an interface, the evaporation of liquid, and the ultimate loss of vapor.

It will be noted that the present floating roof is more efficient than the original Prager-Ulm roof, due to the safe elimination of wavy surfaces, and that it is also more economical due to the simplification and savings in material provided by the use of uniformly thin, flexible, lapwelded plates of any suitable shape, throughout the deck, in the rim, intermediate and ballast weight areas.

The construction of the ballast weight area of the deck should be considered in further detail, with reference to Figures 4, 5 and 6. These figures show a slight modification which is sometimes preferred.

The central drain 20 is connected with the deck surface outside the center weight 18, by a single open diametrical flume 30, not by the drain channels 28 buried below the ballast material as in Figures 1, 2 and 3. Such open construction of the drain passages facilitates the removal of ice, dirt and the like; an operation which is sometimes necessary on all floating roof drains and which may be extremely im-

portant, since any clogging up of the drain may cause the deck to sink in the product.

Incidentally such open construction of the drain passages may also be cheaper, although it may require extra material for sidewalls 31 of the flume, in addition to the peripheral walls 32 surrounding the loose ballast weight material which is preferably used. The saving incident to the use of the open flume construction is due to the fact that the cutting out, fitting up and welding of suitable ports in the wall 32, for the channels 28, can be eliminated.

The open flume construction mentioned separates the center weight 18 into separate bodies of ballast material. A flume 30 of about one foot width will usually be provided, as suggested by the drawing. Thus the separate bodies of ballast material are spaced from one another by an appreciable distance and the ballast weight 18 is no longer a circular unit structure, unless some special provision is made to combine the parts into such a unit structure.

For this purpose I provide a bar 33, extending across each end of the flume 30 adjacent the top of the flume. These bars are preferably buttwelded to the sidewalls 31, as shown at 34. They are installed so that their outsides are flush with the outside of the peripheral wall 32, so that they structurally complete the circular unit formed by the peripheral wall, while leaving the drain flume 30 substantially unobstructed.

I prefer to cover each part of the ballast weight by a removable cover 35. I also prefer to facilitate access to the central drain 20 by locating the drain sump 36 in a circular, central enlargement 37 of the diametrical flume 30. This enlargement may have a diameter of about 4 feet. It can be formed by more or less semi-cylindrical walls 38, secured to the inner ends of the straight side walls 31.

As mentioned above, the improved, circular deck 15 in accordance herewith can be constructed of uniformly thin, flexible plates, usually steel plates of $\frac{1}{16}$ " thickness. Any desired economical pattern of such plates can be used, for instance with plain, rectangular plates throughout, except for suitable sketch plates at the periphery. The plates can be secured together by lapwelding.

In Figure 3 numeral 41 designates the outermost sketch plate of the deck. Numerals 42 and 43 designate intermediate, rectangular plates, curved upwards as explained above. Numerals 44 and 45 designate central plates. The same thickness and flexibility may be used in plates 44, 45 and 41 as in 42 and 43.

As shown in Figure 3, the central plates 44 and 45 may have downward curvature, impressed thereon by the channels 28 welded thereto.

However, it is also possible, as shown in Figure 7, to construct the innermost part of the deck, generally designated by numeral 49, as a simple, flat, straight-sided cone C'. The upward pressure of the liquid product, tending to raise the drain-sump 36 and the empty enlargement 37 of the flume 30, will tend to impose a curvature similar to that shown in Figure 3, but this tendency may be negligible, since the area 37 will generally be small as compared with the complete central area 49 over which the ballast weight is distributed.

For the same reason there is but little danger that the open drain flume area 30 will be raised, interfering with drainage. Such raising up of

the area as would have to be expected is overcome, as mentioned, by the bars 33.

Various other modifications will occur to persons skilled in this art, upon consideration of this disclosure.

This is a continuation in part of my application S. N. 146,503, filed February 23, 1950, as a division of my said application S. N. 122,639, filed October 21, 1949.

10 I claim:

1. In liquid storage apparatus, a substantially centrally drained floating roof having the entire underside immersed in the stored liquid and the deck portion thereof shaped by contour-controlling ballast weight means installed in a generally central, minor but substantial part of the area of the floating roof; comprising an outer, relatively narrow, upstanding, rigid, compression-resisting rim; a single, circular, flexible membrane deck, substantially unreinforced and unobstructed at least throughout the area between the rim and the ballast weight, having its outer part secured to and reinforced by the bottom part of the rim, and comprising substantially the entire area of the floating roof and forming a flat, smooth solid of rotation all vertical cross-sectional contours of which substantially coincide with a curve running outwardly-upwardly throughout the radial distance from the center to the periphery of the deck, with continuous upward curvature between said generally central part and said rim; and ballast weight means distributed over and limited to said generally central part and constituting a sufficient part of the total weight of the floating roof for the purpose of immersing the entire underside of the roof in the stored liquid and cooperating with the stored liquid in shaping the membrane deck into said smooth solid of rotation.

2. Apparatus according to claim 1, wherein said ballast weight means comprises a plurality of bodies of loose material, and an enclosure for each of said bodies; each enclosure being formed by a wall upstanding from said deck, which wall comprises an arc-shaped outer portion and a straight portion intermediate the ends of the arc-shaped portion; a pair of such straight wall portions being arranged in parallel and separated by an open drain flume, and a pair of such arc-shaped wall portions being interconnected by rigid structural means extending across an upper, terminal part of the flume and secured to the walls.

3. Apparatus according to claim 2, wherein said open drain flume extends diagonally of the ballast weight means and has a central, generally circular enlargement, formed by arc-shaped inner portions of said wall of each enclosure.

4. In liquid storage apparatus, a substantially centrally drained floating roof having the entire underside immersed in the stored liquid and the deck portion thereof shaped by contour-controlling ballast weight means installed in a generally central, minor but substantial part of the area of the floating roof; comprising an outer, upstanding, rigid, compression-resisting rim; a single, circular, flexible membrane deck, unreinforced and unobstructed substantially throughout the top and underside thereof, having its outer part secured to the bottom part of the rim, said rim being reinforced at least in said bottom part to which the outer part of the deck is secured, and said deck comprising substantially the entire area of the floating roof inside the rigid rim and

forming a flat, smooth solid of rotation all vertical cross-sectional contours of which substantially coincide with a continuous curve running outwardly-upwardly throughout the radial distance from the center to the periphery of the deck, with downward curvature over said generally central part and with upward curvature between said generally central part and said rim; and ballast weight means distributed over and limited to said generally central part and constituting a sufficient part of the total weight of the floating roof for the purpose of immersing the entire underside of the roof in the stored liquid and cooperating with the stored liquid in shaping the membrane deck into said smooth 15 solid of rotation.

5. Apparatus according to claim 4, wherein said deck forms a flat, smooth solid of rotation all vertical cross-sectional contours of which substantially coincide with a continuous curve running outwardly-upwardly throughout the radial distance from the center to the periphery of the deck, with downward curvature over said generally central part, upward curvature over an intermediate part, and downward curvature adjacent said rim.

REIGN C. ULM.
